Primary Examiner—Catherine R. Oliver

(57) **CLAIM**

I claim the ornamental design of a fishing jig lure, as shown and described.

DESCRIPTION

FIG. 1 is a perspective view of a fishing jig lure of my new design;

FIG. 2 is a top plan view thereof;

FIG. 3 is a side elevational view thereof, the opposite side elevational view being a mirror image thereof;

FIG. 4 is a bottom plan view thereof;

FIG. 5 is a front elevational view thereof;

FIG. 6 is a rear elevational view thereof;

FIG. 7 is a sectional view taken along the line 7—7 of FIG. 2;

FIG. 8 is a sectional view taken along the line 8—8 of FIG. 2;

FIG. 9 is a perspective view of a first modification of the fishing jig lure of FIG. 1;

FIG. 10 is a top plan view of FIG. 9;

FIG. 11 is a side elevational view of FIG. 9, the opposite side elevational view being a mirror image thereof;

FIG. 12 is a bottom plan view of FIG. 9;

FIG. 13 is a front elevational view of FIG. 9;

FIG. 14 is a rear elevational view of FIG. 9;

FIG. 15 is a sectional view taken along the line 15—15 of FIG. 10; and,

FIG. 16 is a sectional view taken along the line 16—16 of FIG. 10.
